UNITED STATES PATENT OFFICE.

DOUGLAS STUART SPENS STEUART, OF LONDON, ENGLAND.

TELEPHONE ACCESSORY.

Application filed November 17, 1927, Serial No. 233,973, and in Great Britain June 14, 1928.

The present invention relates to an improved arrangement for supporting and constructing a flexible tube attached to a telephone transmitter.

5 In my Patent No. 1,654,193, granted Dec. 27, 1927, I have described an arrangement by which a flexible tube extending from a transmitter can be adjusted to stay in any position to which it is put, such tube carrying at its outer end a mouthpiece and enabling conversation to take place without bringing the telephone right up to the mouth of the user.

10 The present invention, while it mainly contemplates improvements in a device of this character, also discloses ideas which are of a much broader scope.

15 One of the features of the present invention concerns the construction and design of the flexible tube which should taper outwards from the transmitter.

20 Another feature of the invention concerns the shape of the mouthpiece, which instead of being flared should preferably be cup-shaped.

25 A third feature of the invention concerns shutter arrangements; one which is manually operated for preventing the sound passing down flexible tubes to the transmitter and which can be controlled at will by the user, and a second which is automatically controlled to prevent dust getting into the receiver.

30 This latter feature is used particularly in conjunction with the fourth feature of the invention which consists of an attachment between the receiver and the mouthpiece whereby when the receiver is placed to the ear the mouthpiece automatically comes in front of the mouth.

35 A fifth feature of my invention, which may be capable of considerably broader application, is a flexible wire arrangement by means of which the flexible speaking tube can be supported in any desired position. This arrangement consists of stranded aluminium wire surrounded by a flexible tube and serves to support the speaking tube by simply threading it through the tube. No 40 claim for this arrangement per se is made in the present case, however, as it constitutes the subject matter of a divisional applica-

tion filed December 27, 1927, Serial No. 242,941.

45 The above and other features of my invention will be better understood by referring to the accompanying drawings, in which Fig. 1 shows the application of the invention to a pillar-type telephone of standard design; Fig. 2 is a side view of the 50 clamp 10 and its support; Fig. 3 is a longitudinal section of the tube and mouthpiece; Fig. 4 is an enlarged sectional view of a portion of the tube; Fig. 5 shows an arrangement for securing the tube to a transmitter when the usual mouthpiece is removed; Fig. 6 shows an alternative arrangement for securing the supporting wire to that illustrated in Fig. 3; Fig. 7 shows the 55 application of the invention to an instrument of the handset type; Fig. 8 shows the manner in which the transmitter is fitted in the box used in the type of instrument illustrated in Fig. 7; Fig. 9 is a face view of the shutter 11; while Fig. 10 shows a section of 60 the earpiece or cup of the receiver 17 with an automatically operating shutter.

65 Referring to Fig. 1, normally the pillar-type telephone 12 rests with its base upon a sloping stand. This stand is provided with a projection and with an upwardly extending socket, in which is fitted a bent rod 40. The fit is a tight one so that the rod 40 can only be removed and replaced by exerting an appreciable force, so that normally it will be held tightly. The rod 40 at its upper end carries a socket 41 in which a bent rod 42 (see Fig. 2) which screws into a thread in the clamp 10 is adapted to slide up and down, being secured in the desired 70 position by means of a screw 43. The clamp 10 is for the purpose of securing the ferrule 13 in a suitable position to engage the transmitter mouthpiece 35. The ferrule 13 is fitted on to the end of a flexible tube 14, the 75 securing of the clamp to the ferrule being effected by means of the screw 15. The ferrule is fitted with a spongy rubber collar 34 adapted to engage with the mouthpiece 35 of the transmitter 16 fitted to the end of the pillar-type telephone, the arrangement being such that when the transmitter is placed on the stand, it tilts, due to the slope 80 of the stand, in such a direction as to press

against the spongy rubber collar 34. This spongy rubber collar is shaped to correspond with the shape of the inner flare of the transmitter mouthpiece 35, and consequently an automatic sealing between the ferrule and the mouthpiece is made when the telephone is placed on the stand as shown, providing of course the position of the clamp 10 and the ferrule have been suitably adjusted previously. The usual receiver 17 is supported by means of a clamp 18 attached to a rod 19 screwed into a light aluminum body 20 shaped as shown, that is, of a suitable shape to engage with the switchhook 21. By this means it is possible to operate the switchhook and support the receiver in the switchhook by placing the body 20, instead of the receiver, in the switchhook. From the upper end of the body 20 extends a bent rod 22 carrying at its end a ferrule 23 and a flexible link 24, which link terminates in a sliding collar 25 embracing the ferrule 26 secured to the end of the flexible tube 14. The flexible tube 14 terminates in a casing 11. In this casing (see Fig. 9) is a shutter device consisting of levers 27 and 28 which, when pressed together, cause the shutters 28^a and 29 to close the passage from the tube 14 to the mouthpiece 30. A leaf spring 31 normally holds the shutters 28^a and 29 apart, so that only when the party using the telephone presses the levers 27 and 28 can the transmitter be rendered dead. This mouthpiece is slightly bent, as shown, and the arrangement is such that when the receiver is lifted and placed to the ear the collar 25 slides along the ferrule 26 and engages at its recessed side a boss on the mouthpiece. This arrangement ensures that the mouthpiece 30 is held in a suitable position so as to be brought automatically in front of the mouth. This enables conversation to be carried on at some distance from the instrument and consequently the pillar-type instrument may rest a foot or two away from the speaker, leaving his desk clear for writing or reading. The flexible link 24 may be of any known type which will remain in the position to which it is put, but preferably it is constructed of aluminium wires stranded together and covered with a flexible tube to prevent bulging of the individual wires. Such an arrangement is practically free from a tendency to return to the position from which it is moved, while at the same time it tends to resist movement and so holds the mouthpiece in the position to which it is placed. The receiver 17 in the position shown might conceivably collect dust which in time might seriously impair its operation. In order to avoid this defect according to the invention an automatically operating shutter is provided in the receiver cap 32. Fig. 10 shows

a view of the inside of the cap, from which can be seen the loosely pivoted shutter 33 supported on a pivot at the right side of the cap, that is, when one is looking at the receiver with the cap end in front. Consequently when the receiver is supported, as shown in Fig. 1, the shutter 33 falls under its own weight and rests on the stop 34^a and closes the opening 34 in the cap (see the dotted-line position in Fig. 10), thus making the receiver dust proof. When the receiver is lifted and held to the ear it will be noted that the receiver is reversed and the shutter falls to the position shown in full lines in Fig. 10 so that the opening 34 is cleared and hearing is in no way affected.

Fig. 3 shows in detail the construction of the tube 14, the ferrule 13 and the mouthpiece 30. For convenience the shutter 11 is omitted, as is also the collar 25. In certain cases it may be desirable not to have any connecting link between the receiver and the mouthpiece, and in such a case the arrangement shown in Fig. 3 could be used exactly as it is. On the other hand it will be readily understood that the arrangements disclosed in Fig. 1 could be incorporated in Fig. 3; in fact Fig. 3 simply explains those details of construction which are not sufficiently shown in Fig. 1.

A description will first be given of the construction of the tube 14. This element is important both as regards its dimensions and as regards its actual structure. As to dimensions, it has been found that the best and most efficient results can be obtained by arranging for the tube to taper slightly so that its diameter at the transmitter end is somewhat less than its diameter at the mouthpiece end. A design of tube which has been found to give most satisfactory results is one in which the diameter of the tube at the transmitter end is $\frac{7}{8}$ " and at the mouthpiece end is $1\frac{3}{16}$ ", this taper being for a tube having a length of $13\frac{3}{4}$ ". For a different length of tube the taper would be proportionate to what it is in the above mentioned case. The inner diameter of the ferrule 13 is so arranged as to continue this taper, which is however slightly accentuated right to the transmitter diaphragm. In the case shown the ferrule 13 is formed of a single casting, which is threaded at one end, and into which the tube 14 is fitted and finally cemented in position, while at the other end it is recessed and fitted with the spongy rubber collar 34 shaped to engage in the inner flare of the transmitter mouthpiece 35.

As regards composition, the construction of the tube will be better followed by reference to Fig. 4. It consists of a closely wound spiral of steel wire 51 embedded in a sheath 52 of pure rubber latex. Outside

the sheath 52 is a brading 53 of silk or like material, which is applied at considerable pressure. Such tubing is highly flexible and is very efficient for sound transmission, and while it constitutes a preferred construction, the invention is not specifically limited thereto as other constructions could be used which might have the advantage of greater cheapness. The design of a speaking tube 10 is well known and any efficient design of speaking tube known could be used with this invention without departing from the spirit thereof. It is apparently important that the wire 51 should be of steel as aluminium wire 15 has been tried and found not to give nearly as efficient a result. Aluminium alloys of the duraluminium type have been tested and found to give good results and might be used in place of steel where lightness is 20 essential. It is not essential that the wires 51, however, should be so constructed that the successive turns of the spiral touch each other, as good results can be obtained where the spirals are separated by some little distance. The flexible tube is supported in the ferrule 26 in much the same way as in the ferrule 13, that is, it is threaded in said ferrule 26 and then cemented in position. On this ferrule is fitted the mouthpiece 30 which is made to have a tight fit so that it can be placed on and removed without using a tool and yet is firmly held. The shape of the mouthpiece is important to give efficient results. It is shown slightly curved, this being because it is more convenient that it should rise slightly towards the user, but there may be circumstances in which it would be advantageous for it to be straight. However, the importance of the shape is not 40 so much in the fact that its axis is bent, as in the fact that the mouthpiece is not flared in the same way as the transmitter mouthpiece 35, that is, in the same way as the usual mouthpiece, but is made more cup-shaped so that actually the flare first increases and then decreases, whereas in the ordinary mouthpiece it increases more and more. Actually, in fact, the extreme end of the mouthpiece is substantially parallel 45 to the axis. In order to support the tube 14 a flexible wire arrangement 54 is provided, which is similar in construction to the flexible link 24. This flexible wire 54, as shown, also consists of a number of carefully annealed aluminium wires 55 stranded together and tightly covered by a flexible tube 56 so as to prevent the stranded wires bulging when the flexible wire is bent. The flexible tube 56 is of well known construction 60 consisting of an interlocking helical winding. The aluminium wires are highly flexible and can be bent as desired and stay in the position in which they are put. The flexible tube round them secures them in position so that they cannot bulge and so enables 65 a considerable weight to be supported at some distance from the mouthpiece. This has the advantage that the mouthpiece may be supported independently of the flexible link 24, when once it is adjusted to a suitable 70 position. In fact in certain cases the flexible link 24 could be entirely dispensed with, except that in such event it would be necessary for the subscriber to take one hand for adjusting the receiver to his ear and 75 the other hand to adjust the mouthpiece. In any case the internal flexible wire 54 serves to reduce the strain on the user by taking the weight of the mouthpiece. To secure the flexible wire in position it is pinched 80 into a tube 57, while being free to slide in tube 56, which sliding is necessary to allow for free play when the tube 14 is bent. Actually a pin 59 could be provided in addition to the pinching, or separately therefrom, 85 but the pin 59 by itself, it should be mentioned, is somewhat unsatisfactory in view of the flexible wire 54 being stranded, and it is found that by pressing the thin tube 57 twice, as shown at 60, the flexible wire 90 95 95 100 105 110 115 120 125 130 135 140 145 150 155 160 165 170 175 180 185 190 195 ward bend, as clearly shown in Fig. 3. This spring 66 is anchored on a ring 67 at one end of the ferrule 13. The arrangement as shown and described has proved from experimental tests to be highly efficient for sound transmission and enables the transmitter to receive sound, even when the mouth is two or three inches away from the mouthpiece, as loud as when the speaker has his mouth right up to the ordinary mouthpiece in accordance with the instructions he receives from the telephone operating authorities.

Fig. 5 shows an alternative arrangement where the ferrule 13 screws directly into the casing 16 of the transmitter, that is, where the ordinary mouthpiece is removed.

In this case it is possible to connect a wire 68, which may be spiral or otherwise, from the tip of the tapered tube 57 to the nut 69 by which the transmitter capsule is connected to the diaphragm 62. This is of advantage because a certain amount of the sound transmitted down the mouthpiece is actually transmitted along the flexible wire arrangement to the tube 57, and furthermore transmission of sound through metal is so much more efficient than the transmission of sound through air that an appreciable magnification of the sound can be obtained.

Fig. 6 shows an alternative arrangement for anchoring the flexible wire 54. The stranded wires 55 in this case are bent round so as to extend first in a radial direction through a slot in the ferrule 13 and then in a circumferential direction in a groove 70. The ferrule 13 is threaded in a similar manner to that shown in Fig. 4, so as to engage with the transmitter casing 16, but the thread in this case is made somewhat longer so that a nut 71 can be screwed on to secure the stranded wires 55 in position. The ferrule can then be screwed into the casing 16. A recess 72 is bored in the end of the ferrule 13 so that a fine spiral spring 73 can be fitted therein. This spiral spring 73 serves the same purpose as the spiral spring 65, but in this case it is provided near the transmitter instead of in the mouthpiece. If desired, of course, spiral springs can be provided at both ends. It is found that the width of the material forming the spiral spring, that is, the dimension parallel to the axis, should be appreciable, say at least $\frac{1}{16}$ " and even as much as $\frac{1}{4}$ " or larger.

Figs. 7 and 8 show a modification in which the receiver 101 is of the watch type, and therefore the whole arrangement can be made to resemble a handset, except of course that the transmitter is not portable. The switch-hook could then take the form of a cradle switch of known type. The instrument would therefore comprise a handle 100, through which passes a tube 102, to which

the receiver 101 is secured at one end, while the other end is bent and has secured to it a clamp 103 by means of a screw 104. The clamp 103 when tightened up is free to rotate on the ferrule 105, but prevented from having longitudinal motion by means of the collars 106 and 107. The mouthpiece 108 is secured to the ferrule 105 at one side while the other side of the ferrule is secured to a flexible tube 109 of similar design and structure, and similarly proportioned to the flexible tube illustrated in Fig. 3. The flexible tube 109 terminates at its other end in a ferrule 110, which is tapered at its inner end as seen in Fig. 8, and provided with a thread for engaging with the transmitter casing 111. The transmitter casing is mounted inside the instrument box 115 by means of a bracket 113, and consequently the transmitter is always vertical and is not liable to damage. A spongy rubber collar 114 is provided in the opening of the instrument box 115 so as to make the joint of the transmitter air-tight. In this way the transmitter is very well protected from external sounds, the only sounds which can affect the transmitter being those conveyed through the tubing 109 or by mechanical vibration, and mechanical vibration if present can be readily overcome by arranging that the support for the transmitter casing 111 is made non-rigid. The box 115 carries a boss 116 on its upper side, through which slides a rod 117, secured to a cradle support 118. The cradle has two fork members 119 and 120, in which the handle 100 can rest. The weight of the receiver and handle is such as to operate satisfactorily through the rod 117 the usual contact springs (not shown), so that the construction of the instrument follows general practice. There are, however, two modifications, one being that the handle points towards the user. This will be recognized in that the slope of the instrument is on the side towards which the handle 100 points. On this slope in an automatic instrument can be fitted a dial switch, or the dial switch may be supported vertically alongside the transmitter. The receiver cord 121 will be seen extending from the receiver through the tube 102 and connected by supporting clips 122 and 123 to the flexible tube 109 and thence into the instrument in the usual manner through a ferrule not shown. To use the instrument it will be clear that all that is necessary is for the user to take hold of the handle 100 and lift the receiver, when the mouthpiece and the earpiece automatically come into position ready for use. Normally the handset is placed to the left ear, but with the arrangement of the clamp 103 it is possible for the handle to swivel to the other side of the mouthpiece, so that a person wishing to use his right ear

could do so without any difficulty, the cord 121 being left sufficiently slack for this purpose, as shown.

I claim:

5. 1. In combination, a telephone transmitter, a mouthpiece, a flexible tube connecting said transmitter to said mouthpiece, and a self-sustaining flexible support located inside the tube for maintaining said tube and 10 mouthpiece in any adjusted position.
2. In combination, a telephone transmitter, a mouthpiece, a flexible tube, a ferrule for connecting one end of said tube to said mouthpiece, a second ferrule for connecting the other end of said tube to said transmitter, a self-sustaining flexible wire support located inside the tube for maintaining said tube and mouthpiece in any adjusted position, and means for securing said 20 flexible wire within said ferrules.
3. In combination, a telephone transmitter, a mouthpiece, a flexible tube, a ferrule for connecting one end of said tube to said mouthpiece, a second ferrule for connecting 25 the other end of said tube to said transmitter, a flexible wire support comprising a stranded cable of aluminum wires, and a flexible interlocking helical tube closely surrounding said wires, and means for securing 30 the ends of said support centrally in said ferrules.
4. In combination, a telephone transmitter, a mouthpiece for said transmitter, a flexible tube extending from said mouthpiece to said transmitter, a self-sustaining flexible support inside said tube to maintain the tube and the mouthpiece in any adjusted position, a receiver, and a self-sustaining flexible link connecting said mouthpiece to said receiver so arranged that when 40 the receiver is placed to the ear the mouthpiece comes in front of the mouth.
5. In combination, a telephone transmitter, a mouthpiece for said transmitter, a flexible tube connecting said mouthpiece to said transmitter, a self-sustaining flexible support inside the tube for maintaining said tube and mouthpiece in any adjusted position, an instrument on which said transmitter is mounted, a receiver, a contact operating support for said receiver, a member attached to the receiver and adapted to rest in said support, and a link connecting said member to said mouthpiece arranged so 55 as to bring the mouthpiece in front of the mouth when said member is lifted from said support and the receiver is placed to the ear.
6. In combination, a telephone transmitter, a mouthpiece for said transmitter, a flexible tube connecting said mouthpiece to said transmitter, an instrument on which said transmitter is mounted, a receiver, a contact operating support for said receiver, a rigid attachment to said receiver adapted 60 to rest in said contact operating support, and a link connecting said receiver to said mouthpiece arranged so as to bring the mouthpiece to the mouth when the receiver is placed to the ear.
7. In combination, a telephone transmitter, a mouthpiece for said transmitter, a flexible tube connecting said mouthpiece to said transmitter, a receiver, a flexible link connecting said mouthpiece to said receiver, a contact operating switchhook for supporting said receiver, an attachment adapted to engage said support and hold said receiver in an appropriate position relative to said mouthpiece, and an automatically operating shutter device to close the 70 aperture in said receiver when supported by the switchhook and open said aperture when placed to the ear.
8. In combination, a telephone transmitter, a mouthpiece for said transmitter, a flexible tube connecting said mouthpiece to said transmitter, a self-sustaining flexible support inside the tube for maintaining said tube and mouthpiece in any adjusted position, an instrument on which said transmitter is mounted, a receiver, a contact operating support for said receiver, a member attached to the receiver and adapted to rest in said support, and a connection between said member and said mouthpiece arranged 75 so as to bring the mouthpiece in front of the mouth when said member is lifted from said support and the receiver is placed to the ear.
9. In combination, a telephone transmitter, a mouthpiece for said transmitter, a flexible tube connecting said mouthpiece to said transmitter, an instrument on which said transmitter is mounted, a receiver, a contact operating support for said receiver, a rigid attachment to said receiver adapted to rest in said contact operating support, and a connection between said rigid attachment and said mouthpiece arranged so as to bring the mouthpiece to the mouth when the receiver is placed to the ear.
10. In combination, a telephone transmitter, a mouthpiece for said transmitter, a flexible tube connecting said mouthpiece to said transmitter, a self-sustaining flexible support inside the tube for maintaining said tube and mouthpiece in any adjusted position, an instrument on which said transmitter is mounted, a receiver, a contact operating support for said receiver, a rigid attachment to said receiver adapted to rest in said contact operating support, and an adjustable link connecting said receiver to said mouthpiece arranged so as to bring the mouthpiece to the mouth when the receiver is placed to the ear.
11. A telephone construction according to claim 6, in which the adjustable link connects the rigid receiver attachment to the mouthpiece.
12. In combination, a telephone transmit-

ter, a mouthpiece for said transmitter, a flexible tube comprising a spiral of wire of aluminium alloy of the duraluminium type surrounded by rubber latex and by tightly 5 braided fabric for connecting said mouthpiece to said transmitter, an instrument on which said transmitter is mounted, a receiver, a contact operating support for said receiver, a rigid attachment to said receiver

adapted to rest in said contact operating support, and an adjustable link connecting said receiver to said mouthpiece arranged so as to bring the mouthpiece to the mouth when the receiver is placed to the ear.

In testimony whereof I hereunto affix my 15 signature this 7th day of November, 1927.

DOUGLAS STUART SPENS STEUART.
